CLAIM

The ornamental design for an interchangeable skate blade as shown and described.

DESCRIPTION

FIG. 1 is a perspective view of the interchangeable skate blade in accordance with the present design;

FIG. 2 is an enlarged view of portion 2 of FIG. 1;

FIG. 3 is a right-side view thereof;

FIG. 4 is an enlarged view of portion 4 of FIG. 3;

FIG. 5 is a top view thereof;

FIG. 6 is a bottom view thereof;

FIG. 7 is a front view thereof;

FIG. 8 is a rear view thereof; and,

FIG. 9 is a left side view thereof.

The evenly spaced broken line showing of portions of an ice skate blade is included for the purpose of illustrating portions of the “article” and forms no part of the claimed design. The dash-dot-dot-dot broken line disclosure represents the boundary highlighting enlarged figures.
